US00D960224S

(12) **United States Design Patent** (10) **Patent No.:** **US D960,224 S**
Tadesse (45) **Date of Patent:** **** Aug. 9, 2022**

(54) **UNIVERSAL ADJUSTABLE MOUNT
ADAPTER**

(71) Applicant: **Sandmarc, LLC**, San Diego, CA (US)

(72) Inventor: **Abel Tadesse**, San Diego, CA (US)

(73) Assignee: **Sandmarc, LLC**, San Diego, CA (US)

(**) Term: **15 Years**

(21) Appl. No.: **29/747,623**

(22) Filed: **Aug. 24, 2020**

(51) LOC (13) Cl. **16-05**

(52) U.S. Cl.

USPC **D16/242**

(58) **Field of Classification Search**

(57) **CLAIM**

The ornamental design for a universal adjustable mount adapter, as shown and described.

DESCRIPTION

FIG. 1 is a front perspective view of a universal adjustable mount adapter showing my new design;

FIG. 2 is a front view of the universal adjustable mount adapter of FIG. 1;

FIG. 3 is a rear view of the universal adjustable mount adapter of FIG. 1;

FIG. 4 is a left side view of the universal adjustable mount adapter of FIG. 1;

FIG. 5 is a right side view of the universal adjustable mount adapter of FIG. 1;

FIG. 6 is a top view of the universal adjustable mount adapter of FIG. 1;

FIG. 7 is a bottom view of the universal adjustable mount adapter of FIG. 1; and,

FIG. 8 is a rear perspective view of the universal adjustable mount adapter of FIG. 1.
